UNDERGARMENT

Filed Sept. 30, 1943

Monroe M. Messing,
By J. R. Paris. Attorney

This is a continuation-in-part of my application for a patent filed on Jan. 10, 1941, Serial No. 382,863, entitled "Undergarment," and is being filed in accordance with the provisions of the Patent Act of 1952, Section 111, which provides that a continuation-in-part application may be filed within two years from the date of the original application.

It is the purpose of this application to provide an undergarment which is particularly designed for use with a woman's outer dress, and which is designed to provide a smooth, flowing line and to eliminate the need for a girdle or belt.

UNITED STATES PATENT OFFICE

UNDERGARMENT

Monroe M. Messing, Lawrence, N. Y.

Application September 30, 1943, Serial No. 504,469

2 Claims.

(Cl. 2--224)

The present invention relates to a woman's nether undergarment of the step-in or pantee type.

A principal object of the present invention is to provide a garment of this type, which fits snugly in its waist portion, which hangs comfortably and loosely around the thighs and drops and flares downwardly with the result that it produces no disturbing lines in the outer dress of the wearer and rather, by its flare and drapes, the undergarment of the present invention gives body to the outer dress and aids it in maintaining graceful lines.

Another object of the present invention is to provide a garment of this character, which is made easily, simply and economically from a minimum number of pieces with a minimum number of operations.

A further object of the invention is to provide a garment of this type which, although free of gathers, still provides ample room and fullness to enable the wearer to assume all active positions without discomfort and still to obviate the bunching of the material of the garment with the consequent disfigurement of the appearance of the outer garment or dress.

Thus, except for the reinforcing strips at the waist and side opening and the trimming band around the leg bottoms, the garment consists of four substantially equal panels of suitable woven textile material, having its bottom edge and its outer side edge cut on the bias. The result is that the garment made of such four panels gives the advantages set forth above.

Other objects and advantages of the invention will be apparent to persons skilled in the art from the following specification and the accompanying drawing.

Fig. 1 is a front perspective view of the garment.

Fig. 2 is a sectional view on line 2—2 of Fig. 1.

Fig. 3 shows the two front panels; and

Fig. 4 shows the two back panels.

Referring to Figure 3, the two front panels of the garment 10 and 11 are duplicates, and have slightly concave upper edges 12, substantially straight outer side edges 13, concave inner edges 14, and somewhat convex bottom edges 15. These panels are relatively narrow at the top and diverge outwardly and downwardly. The edges 13 are substantially shorter than the edges 14 and the edges 15 are directed upwardly and outwardly. They also have crotch portions 21 as shown.

The back panels 16 and 17 are also duplicates and are of substantially the same size as the

front panels, except that they are cut so as to provide additional fullness in the seat. Thus the top edges 18 are of substantially the same length as the edges 12 of the front panels and the outer side edges 19 are of the same length as the edges 13 of the front panels. The inner edges 20 differ somewhat from the edges 14 in that they are longer and have convex portions 22 to provide fullness in the seat. The lower edges 23 are curved and directed the same way as edges 15 of the front panels, but the crotch portions 24 are somewhat longer than the crotch portions 21. As in the front panels, the edges 19 are substantially shorter than the edges 20.

An essential part of the present invention lies in the manner these panels are cut with relation to the direction of weave as indicated. It will be observed that the direction of weave is not quite in line with any of the edges of the panels, that the outer edges 13 and 19 of the front and back panels respectively are cut substantially on the bias line of the weave, that the bottom edges 15 and 23 of the front and back panels respectively are cut substantially on the bias line of the weave, that the top edges 12 and 18 of the front and back panels respectively are cut only slightly out of the line of weave, and that the inner edges 14 and 20 are partly in line with the weave and partly slightly out of line of weave. As will be seen from a later more detailed description of the construction of the garment, the bias cut of the edges 13, 15, 19 and 23 serve to enhance the comfort to the wearer of the garment and also serve to permit the garment to hang loosely from the hips and to flare and drape gracefully.

In assembling the garment the edges 14 of the front panels are joined by a fagoted seam 25, the edges 22 of the back panels are similarly joined by a fagoted seam 26, panels 10 and 16 are joined by a fagoted seam 27 uniting the edges 13 and 19, and the panels 11 and 17 are joined by a fagoted seam 28 leaving the upper portion open as shown, to provide the side opening 29. The reinforcing tape 30 is then sewed around the top edge of the garment, leaving the opening 29 free and open. The fly 31, which consists of a longitudinally folded strip of fabric, is then sewed to the free portions of the edges 13 and 19 in the opening 29. The portion of the fly attached to the front panel 11 is folded against the inner face of the panel and the button holes 32 and 33 are formed through the fly 31 and the superposed edge of the front panel and

buttons 34 are sewed to the other portion of the fly.

At this point the garment is still open at the crotch. Before the crotch is closed the trimming band 35 is sewed to the two legs and the crotch is then closed by a single cross seam completing the leg encircling bands at the bottom of each leg and also uniting the crotch portions of panels 11 and 17 together and the crotch portions of the panels 10 and 16 together. The trimming band 35 at the bottom extends downwardly from the crotch and adds to the comfort of the wearer.

The present garment is devoid of all gathers and free of any tendency to ride up on the wearer or to bunch or in any manner to impart to the outer garment an unsightly appearance.

At the top and in the adjacent region the garment fits snugly, and the main body of the garment hangs loosely from the wearer's hips and flares and drapes gracefully, such drapes following largely the warp of the weave; at the same time substantially all stresses to which the garment is subjected are on the bias of the weave, where the material of the garment is substantially elastic thus enhancing the comfort of the garment and increasing the life of the garment. The fagoted seams in this garment, lend to the elasticity of the garment in the direction of stress.

I claim:

1. A bifurcated woman's nether undergarment made of woven textile material, said garment having an upper body portion designed to fit snugly around the body in the region of the waist of the wearer, and having leg portions integral with said upper portion designed to hang

loosely from the wearer's hips and to flare and drape about the thighs of the wearer, said garment comprising two front panels united along their inner edges and two back panels united along their inner edges, each panel having a downwardly diverging outer lateral edge substantially shorter than its inner lateral edge and an upwardly and outwardly directed bottom edge, the outer edges of the front panels being united with the outer edges of the back panels, these edges being cut on bias lines of the weave and providing extensibility in the garment along the lines of stress in the garment when worn.

2. A bifurcated woman's nether undergarment made of woven textile material, said garment having an upper body portion designed to fit snugly around the body, in the regions of the waist of the wearer, and having leg portions integral with said upper portion designed to hang loosely from the wearer's hips and to flare and drape about the thighs of the wearer, said garment comprising two front panels united along their inner edges and two back panels united along their inner edges, each panel having a downwardly diverging outer lateral edge substantially shorter than its inner lateral edge and an upwardly and outwardly directed bottom edge, the outer edges of the front panels being united with the outer edges of the back panels, these edges being cut on bias lines of the weave and providing extensibility in the garment along the lines of stress in the garment when worn, the inner edge of each panel being curved to provide fit and fullness, said panels being joined by elastic seams.
